STRIP METAL WINDING BLOCK

James R. Coe, Watertown, Conn., assignor to The
American Brass Company, Waterbury, Conn.,
a corporation of Connecticut

Application March 24, 1933, Serial No. 662,489

12 Claims. (Cl. 242—78)

This invention relates to new and useful improvements in winders and has particular relation to a winder mechanism for reeling strips of sheet metal stock.

5 While the means of the present invention is of general application it is particularly useful with an arrangement such as shown in my application Serial Number 659,745, filed March 6, 1933, now Patent Number 1,965,219, dated July 3, 1934 10 15 wherein the present winder may be used for rapidly unwinding the metal from the spools and winding it into reels after the metal has been reduced to the desired gauge, without removing the spools from the mill or delaying the operation of the mill in any way.

An object of the invention is to provide a means for rapidly removing metal from a spool and reeling the metal as it is so removed whereby the spools are released for further use about a mill.

20 Another object is to provide a winder which may be operated at high speed and with a minimum of manual effort.

Other objects and advantages will become apparent from a consideration of the following detailed description taken in connection with the accompanying drawings wherein a satisfactory embodiment of the invention is shown. However, it will be understood that the invention is not limited to the details disclosed but includes 25 30 all such variations and modifications as fall within the spirit of the invention and the scope of the appended claims.

In the drawings:

Fig. 1 is a top plan view of the improved winder, 35 the control clutch therefor being shown in section;

Fig. 2 is a side elevational view of the machine, the view being taken looking from the lower side of Fig. 1 and part of the clutch and brake being 40 broken away;

Fig. 3 is an end elevational view, the view being taken looking from the right in Fig. 2;

Fig. 4 is a longitudinal sectional view through the machine;

Fig. 5 is a transverse sectional view taken substantially along the line 5—5 of Fig. 4;

Fig. 6 is a view partly in elevation and partly in section and showing the operation of a stripper means employed;

Fig. 7 is a view looking from the left in Fig. 6; and

Fig. 8 is a detail elevational view showing the clutch operating means as viewed from the left in Fig. 2.

45 Referring in detail to the drawings, the im-

proved machine includes a bed 10 supported by a base 11 of any suitable construction, that shown including vertical webs 12 and 13. Other vertical webs than those numbered 12 and 13 and best shown in Fig. 5, may be arranged in any desired 5 relation to one another so as to give the desired stability to the machine, and the machine may be anchored or secured in place as by bolts 14 embedded in a floor or concrete block 15.

At spaced points along the bed 10 a pair of 10 brackets 16 and 17 are mounted and these brackets at their upper portions carry bearings 18 and 19 respectively in which is mounted a shaft 20. Bracket 17 is mounted adjacent one end of the bed 10 while bracket 16 is arranged intermediate 15 the ends of the bed and it will be noted that the shaft 20 extends entirely through bearing 18 and includes a forwardly projecting portion 21 carrying a drum 22 disposed over the forward end portion of the bed 10.

20 This drum 22 includes hub portions 23 and 24 secured to the shaft extension 21 as by keys 25 and 26 and it will be noted that the key 25 enters a flanged cap 27 secured on the shaft as by nuts 28, and which element 27 forms a hand 25 wheel by which the drum may be rotated. From this it will be appreciated that the drum 22 is rigid with the shaft 20 and that when said shaft is rotated the drum will also be rotated. To rotate the drum the shaft 20 is driven as by an 30 independent electric motor 29 mounted on any suitably located base 30 and this motor directly drives a pulley 31 over which is trained a belt 32 the latter being also trained over a relatively 35 large pulley 33 loose on the shaft 20 so as to turn thereon.

40 Pulley 33 forms an element of a clutch and has its opposite surfaces covered with facings 34 and 35 of frictional material as cork, asbestos or the like, and a clutch element 36 is keyed to the shaft 20 as at 37 and cooperates with the frictional surface 34. A second clutch element 38 is splined on shaft 20 as at 39 so as to slide longitudinally thereon but rotates with the shaft, and it is adapted to cooperate with the frictional surface 35 45 of pulley 33. When clutch element 38 is in its disconnected position as shown in Fig. 2 the motor 29 if operating will simply drive the pulley 33 without imparting any turning movement to the shaft 20 and the drum 22.

50 When clutch element 38 is in connected position or in clutching engagement the pulley 33 is gripped between clutch elements 36 and 38 and these latter being keyed to the shaft any movement of the pulley will be imparted to the 55

shaft and the drum 22 will be rotated. If desired, the belt 32 may be passed over an idler 40 mounted as in bracket 41 whereby to guide the belt and maintain it under tension and by which 5 tension of the belt may be adjusted. As above suggested, the clutch element 38 is slideable to and from clutching engagement with the pulley 33 and the means for sliding and clutch includes a grooved collar 42 forming part of the clutch 10 element and into the groove of which extend shoes 43 carried by a yoke 44 mounted on a rod or shaft 45 rotatably supported in bearings 46.

Secured to the outer end of shaft 45 is a downwardly extending arm 47 to the lower free end 15 of which is pivoted at 48 a forwardly extending link or rod 49 in turn connected to a rod 50 as by a turn buckle 51 to provide adjustment. At its forward end rod 50 is pivotally connected at 52 with an upwardly extending arm 53 fixed to 20 a short shaft 54 mounted in a bearing 55. Fixedly secured to the short shaft 54 is a foot piece 56 adapted to be manually depressed to shift clutch element 38 to its disconnected position.

When the clutch element is to be disconnected 25 the free end portion of the foot piece 56 is depressed into the position in which it is shown in Figs. 2 and 8 and this results in a partial turning of the shaft 54 so that arm 53 is rocked forwardly drawing forwardly the links or rods 49 30 and 50 whereby arm 47 turns shaft 45 to have the yoke 44 move the clutch element 38 to disconnected position. A relatively heavy coil spring 57 is secured at its lower end to an arm 58 secured to the foot piece 56 and at its upper 35 end this spring is anchored to a table or shelf 59 and tends to raise the pedal 56 the purpose of which will later be more fully set forth. A second coil spring 60 is secured at 61 to the rod 49 and has its other end portion secured to a bolt 40 62 adjustable through a bracket 63 whereby the tension of spring 60 may be varied.

It will be apparent that the springs 57 and 60 normally tend to shift the operating parts so as to bring the clutch element 38 into engagement 45 with the frictional surface 35 of the pulley 33 whereby to push the pulley against the clutch element 36 and clutch the pulley to the shaft 20. Therefore, when the drum 22 is to be rotated the operating parts for the clutch element are simply released to be shifted by the springs 57 and 60 and these springs close or engage the clutch so that the drum will be driven by the motor 29. When rotation of the drum is no longer desired foot piece 56 is depressed against the action 55 of the springs and clutch element 38 moved to disconnected position.

With the foot piece sufficiently depressed a pivoted dog or catch 64 is forced inwardly by a spring pressed plunger 65 and the said dog engages over the upper surface of the foot piece as best shown in Fig. 8. This locks the parts with the clutch disengaged permitting the drum 22 to be easily turned by hand to properly position the slot for insertion of the free end of the succeeding strip. After the clutch is disengaged by partial depression of the pedal further downward movement of the foot piece will bring a cone surface 66 on the clutch element into engagement 65 with a similar surface 67 of a housing-like portion 68 whereby a braking effect is obtained and rotation of the shaft will be instantly stopped. To again bring about rotation of the drum it is but necessary to force the dog 64 rearwardly or 70 toward the right in Fig. 8 thereby releasing the 75

foot piece 56 so that the springs 57 and 60 may act.

The drum 22 is to be operated or rotated to wind or reel strips of sheet metal stock and such stock may be delivered to the winder by any suitable means. As here shown, the stock 89 is delivered to the winder on spools 90 the flanges 91 of which are rotatably supported on rollers 92 mounted in a frame 93 of a carrier 94 including rollers 95 operating in tracks 96. The frame 94 10 includes upwardly extending arms 97 supporting a roller 98 which prevents the spool 90 moving off the carrier. Drum 22 is provided with two or more slots 99 adapted to receive the end of the stock 89 drawn off the spool 90 as shown at 100 15 in Figs. 3 and 7. When this has been accomplished the clutch may be engaged whereby to have the motor 29 rotate the drum 20 to wind or reel the stock 89 from the spool 90 onto the drum 22. 20

An upright 101 is carried by the bed 10 and at its upper end includes a bearing portion 102 through which extends a shaft 103 on which is pivoted a hub portion 104 of a frame 105. This frame includes side portions 106 and 107 connected at their ends as by a strap 108 and connected intermediate therein as by a strap 109. These straps serve as spacing means and in addition the intermediate portions of the sides 106 and 107 of the frame are connected by a pin or 30 rod 110 on which is disposed a roll 111. A flexible element or means 112 here disclosed as a piece of leather belting is connected at its respective ends to the straps 108 and 109 as by bolts 113.

Projecting forwardly from the upright 101 is 35 an arm 114 through which extends a pin 115 to which is connected a hand lever 116 and a cam 117. The side 107 of frame 105 carries a projecting portion 118 adapted to be engaged by the cam 117 whereby the lever 116 may be operated to 40 raise and lower the frame 105 to carry the flexible means 112 toward and from the drum. A pin or other stop 119 may limit downward movement of the cam, and the lever 116 may be manually pressed to have the cam pressed downwardly on 45 the frame 105 through a lug 105a whereby to bring the belt 112 into more or less tight engagement with the metal being reeled onto the drum whereby to tension said metal and also prevent injury to the metal or to the operator that might result 50 if the last end of the strip were allowed to run wild at the completion of the winding operation until the revolution of the block or winding drum was stopped. When an end of a strip has been inserted into one of the slots 99 and during the 55 first few revolutions of the drum it is desirable that the flexible means 112 be pressed into tight engagement with the metal to fully tension it. There may be a guard 143 on the opposite or front side of the drum and extending upwardly 60 from the bed to hold the metal should it tend to unwind on the drum when it is stopped. Its curved surface may be covered with a protecting facing 144. A similar but lower guide or guard 145 is provided on the opposite side of the drum. 65 A guide table or shelf 59 as clearly shown in Fig. 3 is placed in front of the drum.

The sheet metal stock is wound onto the drum 22 in the form of a reel 120. Means are provided for stripping a finished reel from the drum and this means includes a stripper ring 121 normally disposed about one end portion of the drum and having a groove 122 in its outer surface. A pair of spaced bars or projections 123 are secured to the ring 121 as by screws 124 and these bars are 75

slidable in grooves 125 formed on the outer surface of the drum. As here disclosed these bars are of such thickness as to be received in the grooves and lie substantially flush with the outer surface of the drum and when the metal is being wound on the drum to form the reel 120 the metal is wound over the projections 123.

Bed 11 is slotted in its forward portion as at 126 and a slide 127 is mounted on the bed and includes a depending portion 128 operating through this slot. The bed includes portions 129 providing guideways for the slide 127 and on its forward portion the slide carries a yoke 130 of the upper portions of the arms 131 of which each carry a shoe 132 entering into the groove 122 in the stripper ring 121. Arranged below the bed 11 and between the webs 12 and 13 is a cylinder 133 within which is a piston 134 provided with a piston rod 135 connected at its forward end as by a head 136 with the depending piece 128 of the slide 127. The head and portion 128 are pivotally connected as at 137. Fluid under pressure such as air may be supplied to and exhausted from the cylinder through any suitable means as 25 a pipe 139 and the flow of fluid through this pipe is controlled as by a four way valve 140 located convenient for manipulation by the operator.

In the operation of the device the metal to be reeled is brought to the winder either on a spool 30 90 mounted on a carrier 94 or otherwise. The stripper ring 121 is in its normal position at the inner end of the drum as best shown in Figs. 1 and 4 and the clutch is disengaged. By manipulating the lever 116 the operator has raised the 35 frame 105 to an elevated or out of the way position as suggested by the broken lines in Fig. 3. He draws the end portion of the strip 89 from the spool and inserts the end of the strip into one of the slots 99 in the drum. Handle 116 may 40 be operated to lower the frame 105 to have the flexible means 112 engage the strip and dog 64 may now be shifted to release the foot piece 56 and the springs 57 and 60 will act to engage the clutch to have the motor 29 drive the drum. The lever 116 may be operated to forcefully press the element 112 against the metal as long as desired.

As the drum rotates it will carry the stripper ring 121 with it owing to the presence of the projections 123 in the grooves 125 in the drum. However, the stripper rings and the projections are slidable on the drum and when a reel 120 has been formed the clutch is disengaged and the element 38 may be forced against the surface 67 of the housing 68 to apply a braking effect to the shaft. The dog 64 acts to lock the clutch element 38 in disengaged position and the valve 140 may now be opened to have the piston 134 force the slide 127 forwardly. Since the yoke 130 is carried by the slide the yoke will be carried forwardly and as its shoes 132 are located in the groove 122 of the stripper ring the said ring and its projections will be carried forwardly. That is, the ring is slid along the drum and strips the reel 120 from or forces it off the drum as suggested in Figs. 6 and 7. The bars 123 in the grooves 125 not only cause the stripper ring to rotate with the drum, but also prevent entrance of the first layer of thin metal between the drum and the stripper ring during the stripping operation, which would prevent proper operation of the stripping ring.

When the reel is practically off the drum its inner end is supported by the projections 123 from which it can be drawn by the operator and 75 allowed to drop, according to the present show-

ing, on a gravity conveyor 141 including rollers 142 whereby it will be carried out of the way as to a slitter or any other desirable location. Before the stripper ring is operated the frame 105 should be elevated, and after a reel has been forced off the drum the stripper ring 121 is withdrawn or retracted to its normal position and an end of a new strip may be inserted into one of the slots 99 after which the frame 105 may again be lowered and the clutch again engaged to have 10 the motor drive the drum to wind the next strip thereon.

From the foregoing description it will be seen that the present machine may be used to rapidly unwind metal or take off metal from a spool 15 90 and to form such metal into a reel whereby the spool is released for further use in a mill. Also, it will be appreciated that the machine may be operated at relatively high speed and that it will form the metal into a tight reel, and 20 that the machine may be conveniently operated with a minimum of manual effort.

Having thus set forth the nature of my invention what I claim is:

1. In a winder, a shaft, means supporting said shaft, a drum connected with said shaft, means to rotate the shaft to rotate the drum to wind metal on the latter, a stripper ring on the drum, said ring slidable along the drum, a projection on said ring and extending forwardly thereof 30 along the drum whereby metal wound on the drum will be wound over said projection, means to operate the stripper ring along the drum to force a reel of metal off an end of the drum and said projection adapted to support the reel 33 of metal until the inner end portion of the same is moved off said end of the drum.

2. In a winder, a shaft, means supporting said shaft, a drum connected with said shaft, means to rotate the shaft and the drum to wind a strip 40 of metal onto the drum, said drum having a groove therein, a stripper ring on the drum, said ring having a portion entering the groove in the drum whereby the ring is rotatable with and slidable along the drum, a slide, said stripper ring having an annular groove therein, a yoke carried by said slide and having arms disposed at the sides of said ring, shoes carried by said yoke and extending into the groove in said ring whereby the ring may turn with the drum relative to the slide and whereby the ring will be moved along the drum as the slide is moved, and means for moving the slide to operate said ring and force a reel of metal off an end of the drum. 50

3. In a winder, a shaft, means supporting said shaft, a drum connected with said shaft, means to rotate the shaft and the drum to wind a strip of metal onto the drum, said drum having a groove therein, a stripper ring on the drum, said ring having a portion entering the groove in the drum whereby the ring is rotatable with and slidable along the drum, a slide, said stripper ring having an annular groove therein, a yoke carried by said slide and having arms disposed at the sides of said ring, shoes carried by said yoke and extending into the groove in said ring whereby the ring may turn with the drum relative to the slide and whereby the ring will be moved along the drum as the slide is moved, and fluid pressure operated means for manipulating the slide to cause the stripper ring to force a reel of metal off an end of said drum. 55

4. In a winder, a drum, means to rotate the drum to wind metal thereon, said drum having a pair of spaced longitudinally extending grooves

- in its surface, a stripper ring on said drum, a pair of projections carried by said ring and extending forwardly thereof and entering said grooves whereby metal wound on the drum will 5 be wound over said projections, means to slide the ring along the drum to force a reel of metal off one end of the drum, and said projections adapted to prevent entrance of the first layer of thin metal between the drum and the stripper 10 ring during the stripping operation and to support the reel of metal until the inner end portion of the same is moved off said end of the drum.
5. In a winder, a drum, said drum having a slot therein into which an end of a strip of 15 sheet metal may be inserted, means to rotate said drum to wind the sheet metal strip thereon, a pivoted frame, a flexible means secured at its respective ends to spaced portions of and carried by said frame, and means to operate said frame 20 toward and from said drum to press the intermediate portion of said flexible means against the metal being wound on the drum whereby to tension said metal and confine revolution of the last or tail end of the strip.
- 25 6. In a winder, a drum, said drum having a slot therein into which an end of a strip of sheet metal may be inserted, means to rotate said drum to wind the sheet metal strip thereon, a pivoted frame movable toward and from said 30 drum, a flexible means carried by said frame, and a manually operated cam means engaging said frame and operable to press the flexible means against the metal being wound on the drum whereby to tension said metal and confine revolution of the last or tail end of the strip.
- 35 7. In a winder, a drum, means to rotate said drum to wind a sheet metal strip thereon, means movable toward and from said drum, a flexible means carried by said movable means, a cam 40 engaging said movable means, and manual means to rock said cam to shift said movable means and press said flexible means against the metal being wound on the drum whereby to tension said metal and confine revolution of the last or tail 45 end of the strip.
8. In a winder, a drum, means to rotate the drum to wind metal thereon, a stripper ring on said drum, a pair of projections carried by said ring and extending forwardly thereof whereby 50 metal wound on the drum will be wound over said projections, means to slide the ring and projection along the drum to force a reel of metal off one end of the drum, and said projections adapted to support the inner end portion of the reel 55 of metal until said inner end portion is moved off said end of the drum.
9. In a winder, a drum, means to rotate the drum to wind metal thereon, a stripper ring associated with said drum and slidably along the
- drum for shifting a reel of metal off an end thereof, said ring including means to support the inner end portion of the reel of metal until said inner end portion is moved off said end of the drum, and means to operate said stripper ring. 5
10. In a winder, a drum, means to rotate said drum to wind a sheet metal strip thereon, a frame including side and end portions, means pivotally mounting one end of said frame, a flexible means connected at its respective ends to the end portions of said frame and located between the side portions of the frame, a pair of vertically spaced lugs on one side portion of said frame, a cam extending between said lugs, and means to operate said cam to selectively engage it with the lugs 10 to rock said frame away from said drum and to rock the frame in the direction of the drum to press said flexible means against the metal being wound onto the drum. 15
11. In a winder, a shaft, a drum on the shaft, 20 a driven clutch element rotatable on the shaft, a slidable clutch element secured to the shaft, spring means normally tending to move the slid- 25 able clutch element into clutching engagement with the driven clutch element whereby to bring about rotation of the shaft and drum to wind metal onto the drum, manually operable means to shift said slidable clutch element against the action of the spring to disconnect the clutch elements, a stationary brake means positioned to 30 be engaged by said slidable clutch element by further movement after the latter is moved to disconnected position whereby to stop rotation of the shaft, and a catch to secure said manually operable means in position restraining said spring 35 means with said slidable clutch element in an intermediate position disconnected from both the driven clutch element and the stationary brake means. 40
12. In a winder, a shaft, a drum on the shaft, 45 a driven clutch element rotatable on the shaft, a slidable clutch element secured to the shaft, spring means normally tending to move the slid- 50 able clutch element into clutching engagement with the driven clutch element whereby to bring about rotation of the shaft and drum to wind metal onto the drum, a brake element in position to be engaged by the slidable clutch element to stop rotation of the shaft, manually operable means to shift said slidable clutch element against the action of the spring to disconnect the clutch elements and to engage the slid- 55 able element with the brake, and means to secure said manually operable means in position restraining said spring means with said slidable clutch element in an intermediate position out of engagement with both the driven clutch element and the brake element. 55

JAMES R. COE.
